UNITED STATES PATENT OFFICE.

HIRAM VAN PELT, OF BATH, NEW YORK.

ROAD-SCRAPER.

Specification of Letters Patent No. 17,529, dated June 9, 1857.

To all whom it may concern:

Be it known that I, HIRAM VAN PELT, of Bath, in the county of Steuben, in the State of New York, have invented a new 5 and Improved Scraper for Scraping Earth; and I do hereby declare that the following is a full and exact description thereof, reference being had to the accompanying drawings and to the letters of reference marked 10 thereon.

My improved scraper is so constructed, that it is, at all times, in the proper position for performing its functions, viz: right side up and right end foremost. It is made 15 with scoops on each of its ends in reverse or alternate positions, which enables it to always present one or the other of its ends for scraping or scooping up the earth. By this arrangement, most of the labor of 20 handling the scraper is avoided, and a considerable saving of time is effected; which would otherwise be expended in turning the scraper back again into a perpendicular position, or at an angle of about forty-five 25 degrees, for refilling, and in changing the position of the team. My arrangement also allows the team to be attached to the scraper by a much shorter chain than is usually employed with the older inventions 30 for scraping, &c., and of obtaining a draft better suited to the propelling power.

By reference to the accompanying drawing, it will be seen that I employ iron rods C, C, on each side of the scraper, for the 35 purpose of attaching the chain E, E, thereto. The said chain is fastened to a loosely sliding ring, which allows it (the chain) to be transferred, on the rods C, C, from one end of the scraper to the other, without being 40 detached therefrom. This arrangement is not only important, but very convenient, as will readily be observed.

After the scoop I, of the scraper, has been 45 filled with the earth, the said scraper is then thrown over, which deposits its contents on the ground. The team is then changed to the rear end, which changes the said rear end to a front end, the scoop of which is ready for excavating as in the 50 former instance. The scoop on said end is then filled and emptied, and vice-versa.

The chain, when the team changes from one end of the scraper to another, does not require to be disconnected, but slides backward, and forward, as the case may be, to 55 its proper position. In this manner, also, I obtain an alternate change of draft, as will readily be perceived.

To enable others skilled in the art to make and use my invention I will proceed to 60 describe its construction and operation.

I construct the sides of my scraper as seen at A, A, in the accompanying drawing, of wood or iron so shaped at the ends as to receive the points or edges which are shown 65 at B, B, which points or edges are to be made of cast or wrought iron or steel. C, C, are the rods on which the chains slide by which a change of draft is obtained from end to end alternately. Handles D, 70 D, for lifting the scraper, as shown in the drawing, are formed on each end of the rods C, C, on which the chains slide, and are extended beyond the point to which the chains can slide; and in a full sized scraper 75 will be about nine inches long.

E, E, are the chains to which the team is attached to the scraper, when in operation.

F, F, is the spreader to be made of wood or iron which keeps the chains apart and 80 separate so as to give the scraper a fair chance to revolve without being entangled in the chains. Swivels may be formed in the chains to prevent them from becoming 85 twisted. A partition H, separates the 85 scoops from each other, as shown in the drawing.

I am aware that a scraper has been made to revolve upon pivots, placed within a suitable frame, and therefore I do not claim 90 such as my invention; but

What I do claim as new and desire to secure by Letters Patent, is—

The alternate arrangement of the scoops I, I, in combination with the draft rods D, 95 D, substantially in the manner, and for the purpose herein set forth.

HIRAM VAN PELT.
